UNITED STATES PATENT OFFICE.

JUDSON E. WRIGHT, OF SAN DIEGO, CALIFORNIA, ASSIGNOR OF ONE-HALF TO CHARLES FREY, OF SAN DIEGO, CALIFORNIA.

TIDE-MOTOR.

1,304,238.

Specification of Letters Patent.

Patented May 20, 1919.

Application filed December 27, 1916. Serial No.139,111.

To all whom it may concern:

Be it known that I, JUDSON E. WRIGHT, a citizen of the United States, residing at San Diego, in the county of San Diego and 5 State of California, have invented certain new and useful Improvements in Tide-Motors, of which the following is a specification.

My invention relates to a motor to be used 10 for developing power from the rise and fall of the tide, and the objects of my invention are, first, to provide a motor of this class with means for storing energy by which power will be produced during the 15 time there is none or but slight movement of the tide; second, to provide a motor of this class in which power will be produced by the revolving of a shaft in one direction as the tide moves either up or down; third, 20 to provide a motor of this class in which one or a large number of units may be used in connection with each other or singly for driving a power shaft; fourth, to provide a motor of this class in which the force of 25 gravity is utilized for producing the power when the tide is practically at a stand still and, fifth, to provide a motor of this class which is simple and economical of construction, durable, easy to operate, continuous in 30 its action, and will not readily deteriorate or get out of order.

With these and other objects in view as will appear hereinafter, my invention consists of certain novel features of construction, combination and arrangement of parts 35 as will be hereinafter described in detail and particularly set forth in the appended claims, reference being had to the accompanying drawings and to the characters of 40 reference thereon which form a part of this specification in which:

Figure 1 is a perspective view of my device for producing power when the tide is active and showing one form of means for 45 storing energy for operating the power shaft when the tide is inactive, all shown in connection with a fragmentary portion of a wharf or supporting structure. Fig. 2 is a detailed perspective view of the guide means 50 upon which the gear racks are shifted. Fig. 3 is a perspective view of the gravity actuated means for operating the power shaft when the tide is inactive from the energy stored while the tide is active. Fig. 4 is a 55 modified form of structure used for storing

energy while the tide is active to be used by the structure shown in Fig. 3 for revolving the power shaft when the tide is inactive or nearly so, and Fig. 5 is a fragmentary sectional view of the sphere carrying wheels 60 showing the pockets for supporting the spheres.

Similar characters of reference refer to similar parts throughout the several views.

The wharf 1, float 2, gear racks 3 and 4, 65 gear 5, gear rack shifting device 6, sprocket 7, shaft 8, shaft 9, gear 10, gear 11, sheave 12, sheave 13, shaft 14, conveyer 15, spheres 16, wheel 17, sprocket 18, sprocket 19, gear 20 and gear 21 constitute the principal parts 70 of my motor. The wharf is preferably composed of three floors 1, 1^a and 1^b placed one above the other and preferably supported by means of transverse beams 1^c and piles 1^d. Beneath the floor 1 and between the 75 piles is a very large float 2 of suitable weight floating in the water, and it is held in its position by means of guides 2^a but permitting it to rise and lower with the rise and fall of the water with the varying tides. 80 Secured to the top of this float are a plurality of pairs of guide members 2^b as shown best in Fig. 2 of the drawings and secured to each pair of guide members 2^b is a pair or gear racks 3 and 4 which are vertically 85 positioned and supported upon said float and held in certain spaced relation to each other by means of cross bars 3^a and 3^b so that the gear 5, with which the teeth of the racks are adapted to engage, will only engage 90 with one rack at a time, said racks being shifted sidewise so that the rack 3 engages with one side of the gear when the tide is rising, and the rack 4 engages with the other side of the gear when the tide is falling, and for shifting said racks I have provided a shifting device 6, mounted on the floor 1^a and adapted to be shifted longitudinally thereon provided with rollers 6^a adapted to engage the outer edges of the 100 racks 3 and 4 for reducing the friction between said shifting device and said gear racks. This shifting device 6 is also provided with a lever 6^b pivotally mounted on the floor 1^a at 6^c, and said lever is pivotally 105 mounted on the shifting device at 6^d so that when said lever is thrown over it shifts and holds said shifting device 6 in a certain shifted position placing one of the racks 3, 4 in engagement with the gear 5. The gear 110

5 is mounted upon the shaft 8 and is re-
volved by said racks 3 or 4 as hereinbefore
described and rigidly secured to this shaft
are a plurality of sprockets 7. In this case
5 I have shown three, but there may be more
or less as desired for forming a unit, and
there may be as many units as desired. This
shaft 8 is supported on the floor 1^a by means
of the bearing 8^a. Mounted on the same
10 floor and spaced from said shaft 8 is an-
other shaft 9 mounted on a bearing 9^a. On
this shaft are a plurality of sprockets 9^b in
line with the sprockets 7, and said sprockets
9^b and 7 are connected by means of the
15 chains 7^a, and mounted on this same shaft
9 is a large gear 10 which engages another
smaller gear 11 mounted on the shaft 11^a,
and mounted on this shaft is a sheave 13
which is provided with a belt 13^a for ex-
20 tending to any driven mechanism it is de-
sired to drive by the motor. The objects of
the gears 10 and 11 are to provide greater
speed to the shaft 11^a, the size of the gears
being made suitable to drive the driven
25 mechanism as desired. Mounted on this
shaft 11^a is also a sheave 12 which is pro-
vided with a belt 12^a which engages a sheave
14^a mounted on a shaft 14 on the floor 1 of
the wharf. Mounted on this shaft 14 is also
30 a sheave 15^a for the conveyer 15 which is an
ordinary endless bucket and belt conveyer
which is supported on a sheave 15^b on the
upper floor 1^b of the wharf. In connection
with the lower end of the conveyer 15 is a
35 track 16^a adapted as a guide for the spheres
16 which is slightly inclined, adapted to roll
the spheres 16 into the buckets which carry
them up to the floor 1^b and there release
them upon a similar track 16^b which is also
40 inclined, adapted to carry the spheres to the
wheel 17 on this same floor where they gravi-
tate into the pockets 17^a in the wheel 17 and
thereby revolve said wheel 17 and are
emptied from the pockets on the floor 1 on
45 to the inclined track 16^a from whence they
gravitate to the conveyer 15. It will be here
noted, however, that when the tide is suffi-
ciently active to produce power in addition
to the raising of the spheres 16 to the floor
50 1^b that the spheres 16 are carried by the
conveyer 16, and the wheel 17 revolves, and
that the wheel 17 is only used for producing
power when the tide is inactive or nearly
so. It will also be here noted that the wheel
55 17 is only one unit of which there may be
a plurality as desired for producing the
proper amount of power. This wheel 17 is
mounted on a shaft 17^a journaled in a bearing
17^c on the floor 1^a and mounted on this
60 same shaft 17^a is a sprocket 18 provided
with a chain which extends to another
sprocket 19 secured to a shaft 19^a which is
journaled in bearings 19^b a suitable distance
from the bearing 17^c and mounted on this
65 same shaft 19^a is a large gear 20 which

engages a gear 21 which is mounted on a
shaft 21^a, and upon this shaft 21^a is se-
cured a sheave 21^b provided with a belt
which extends to the driven mechanism
as desired. It will thus be noted that the 70
mechanism shown in Fig. 3 of the drawings
and just described is an auxiliary mech-
anism for operating the driven mechanism
by means of the spheres 16 stored on the
floor 1^b while the tide is active for use for 75
power when the tide is inactive. In Fig. 4
of the drawings I have shown a modified
form of structure for raising the spheres
from the floor 1 to the floor 1^b from the con-
veyer 15 shown in Fig. 1 of the drawings, 80
the float, wharf, rack, gear 5, spheres and
sphere tracks being the same as is shown in
Fig. 1 of the drawings, and the wheels 17
mounted on the shaft 8 are the same as the
wheels 17 shown in Fig. 3 of the drawings. 85
The spheres 16 are raised from the floor 1
to the floor 1^b by gravitating into the pock-
ets of wheel 17 and are carried upward by
the operation of the floats 2 operating the
shaft 8 as hereinbefore described. It will 90
be here noted that the racks 3 and 4 are
shifted manually, and that the spheres are
controlled in their tracks manually for pro-
ducing proper and continuous power to the
driven mechanism at all times as required 95
by the variations of the activity of the tide.
In order to hold the wheels 17 and sprocket
7 when not in use I have provided pawls 22
to be manually operated for holding the
same. 100

Though I have shown and described a par-
ticular construction, combination and ar-
rangement of parts and certain modifica-
tions, I do not wish to be limited to this par-
ticular construction, combination and ar-
rangement or to these certain modifications,
but desire to include in the purview of my
invention, the construction, combination
and arrangement substantially as set forth
in the appended claims. 110

It is obvious that with this construction
there is provided a tide motor which will
produce power to be utilized by a driven
mechanism while the tide is active, either
rising or falling, that there is provided an 115
auxiliary for providing power to this driven
mechanism while the tide is inactive, that
a sufficient quantity of spheres may be
stored on the floor 1^b to operate the driven
mechanism for a considerable length of time 120
during inactivity of the tide or for repair
of the general mechanism which may be
utilized for producing power as described,
that there may be as many units of the gen-
eral mechanism as is required to produce the 125
required power.

Having thus described my invention, what
I claim as new and desire to secure by Let-
ters Patent is:

1. In a tide motor, a wharf comprising 130

three floors spaced apart one above another, a float adapted to rise and fall with the water below said wharf, a plurality of vertical guides for preventing side movement of 5 said float, a plurality of pairs of gear rack members each pair shiftably connected to said float at their lower ends, a gear revolvably mounted between said rack members on the middle floor of said wharf, means for facilitating the manual shifting of said rack members whereby the opposite members are engaged by said gear, a plurality of wheels mounted on the shaft provided with a plurality of pockets in their outer edge, a track 10 for each wheel for guiding balls to the pockets in said wheel on the lower floor of said wharf, a track on the upper floor for each wheel for guiding the balls from the pockets of said wheels, a plurality of other wheels 15 revolvably mounted on the second floor of said wharf adapted to receive the balls from the tracks in the upper floor whereby said wheels are turned by the weight of said balls for producing power in their descent to the 20 lower floor.

2. In a tide motor, a wharf comprising three floors spaced apart one above another, a float adapted to rise and fall with the water under said wharf, a plurality of wheels revolvably mounted on the second 30 floor of said wharf provided with a plurality of pockets in their outer edges, means connecting said float with each of said wheels for revolving said wheels with the rise and fall of said float in the water, a track for 35 each wheel for guiding balls to the pockets in said wheel on the lower floor of said wharf and a track on the upper floor for each wheel for guiding the balls from the pockets of said wheel, a plurality of other 40 wheels revolvably mounted on the second floor of said wharf adapted to receive the balls from the tracks in the upper floor whereby said wheels are turned by the weight of said balls for producing power in 45 their descent to the lower floor.

In testimony whereof, I have hereunto set my hand at San Diego, California, this 16th day of December 1916.

JUDSON E. WRIGHT.
